GOLF BALL COLLECTOR

F. Warren Wells, Springfield, Mass., assignor to
Blair Manufacturing Company, Springfield,
Mass., a corporation of Massachusetts

Application February 16, 1946; Serial No. 648,100

7 Claims. (Cl. 55—17)

1

This invention relates to improvements in golf ball collectors, and is primarily directed to retrieving means for recovering the golf balls which become scattered over a wide area of a practice driving range.

An object of this invention is the provision of mechanical means which, when drawn, pulled, or pushed over the ground, will pick up golf balls or the like which may be lying on the ground and deposit them in a receptacle provided for receiving them.

A further object of this invention is the provision in mechanical means for collecting golf balls from the ground, of a removable and replaceable receptacle or basket, whereby, when one receptacle becomes full, it may be removed and an empty one substituted, without removing the collecting device from its field of operation.

Still another object of this invention is the provision in a golf ball collecting device, of a construction which provides for separating the golf balls from grass clippings, twigs, and the like, and also for cleaning the balls while they remain in the receiving receptacle.

Another object of this invention is the provision of a golf ball collector which is simple, sturdy, and economical of construction, and one which adapts itself readily and efficiently to operation either as a single unit, or in a gang of units, similar to a gang lawnmower.

These, and other objects and advantages of this invention will be clearly described and disclosed in this specification, the accompanying drawings, and the appended claims.

Broadly, this invention comprises a frame, a shaft journaled in the frame, traction wheels secured on the shaft and driving the same, a plurality of spring fingers secured to the shaft and providing, when the shaft is revolved, a revolving cylinder for forcing golf balls in the path of the cylinder to the rear of the cylinder, a ramp secured on the frame with its front edge in juxtaposition to the ground and to the underside of the revolving cylinder, a removable basket or receptacle supported in the frame to the rear of the ramp, the rear edge of the ramp overhanging the front edge of the basket, whereby, when golf balls are forced rearwardly by the spring fingers on the revolving shaft, they will roll up the ramp and into the basket, the ramp and basket being constructed of perforate material which will permit objects and debris smaller than a golf ball to pass through them to the ground.

2

A preferred embodiment of this invention is illustrated in the accompanying drawings, in which

Fig. 1 is a plan view of my golf ball collector,

Fig. 2 is a cross-sectional view taken on the line 2—2 of Fig. 1,

Fig. 3 is a partial sectional view illustrating the means for securing the spring fingers to the revolving shaft, and

Fig. 4 is a perspective view of one of the spring fingers.

Referring now to the drawings in detail, in which like numerals refer to like parts throughout,

A substantially U-shaped frame 1, having sides 2, a rear wall 3, and forwardly extending ears 4, has a shaft 5 rotatably journaled in the forward ends 6 of the side walls 2. The ears 4 are provided with holes 7 for receiving cables or other suitable connections (not shown), to the drawbar of a tractor or the like. Traction wheels 8 are operatively connected or secured on the ends of the shaft 5 and, when the frame 1 is pulled or pushed across the ground, the traction wheels 8 revolve the shaft 5, in the direction indicated by the arrow in Fig. 2. A swivel wheel or castor 9, supported on the rear wall 3 of the frame 1, provides a rear support for the frame 1, so that the frame 1 has a three-point support by the wheels 8 and wheel 9.

A plurality of U-shaped spring fingers 10, removably secured in the shaft 5, revolve with the shaft 5, and are of such length as to approach, at their lowest position, within a short distance of the ground, so that a golf ball located in the path of the revolving fingers 10 will be forced or kicked rearwardly when contacted by one or more of the fingers 10.

A ramp 11, composed of a plate 12, spacing bar 13, and spaced, parallel rods or bars 14, is secured on the sides 2 of the frame 1 by means of bent end portions 15 of the plate 12, which may be secured on the sides 2 in any suitable manner, such as welding or riveting. The ramp 11 is positioned with the front edge of the plate 12 in juxtaposition to the ground in adjacent to the perimeter of a cylinder formed by the revolution of the fingers 10, and the ramp 11 is slanted upwardly and rearwardly from the front edge of the plate 12, as best shown in Fig. 2. The plate 12, rods or bars 14, and spacing bar 13 may be secured together in any suitable manner, such as spot welding.

A basket or receptacle 16, having a semi-circular bottom 17 and side walls 18, is removably

supported on the sides 2 of the frame 1 by means of clips 19, secured in spaced relationship on the side walls 18. Handle grips 20 are secured on the side walls 18 of the basket 16, thus providing means for lifting the basket out of its supporting frame. The bottom 17 of the basket 16 is preferably made of perforate material, as best indicated in Fig. 1, with the perforations 21 of somewhat smaller size than the diameter of a golf ball. A wire mesh has also been used for the bottom 17 of the basket 16, with satisfactory results. The rear ends of the rods 19 extend over the forward edge of the basket 16, as shown in Figs. 1 and 2.

Wing members 22, secured on the sides 2 of the frame 1, close the gap between the wheels 8 and the basket 16, thus preventing balls forced rearwardly up the ramp 11 from escaping at the sides of the collecting device.

The spring fingers 10 are formed with their base portions 23 bent away from the direction of revolution, as best indicated in Figs. 2 and 4, thus providing a brushing effect on golf balls located in their path. It has also been found that this construction provides a maximum of efficiency, as on the rare occasions when the portion 23 strikes the exact top of a golf ball, the ball is either snapped rearwardly up the ramp and into the basket, or snapped forwardly. In the latter case, the ball will be picked up again as the machine approaches its new position. As shown in Fig. 3, the spacing of the U-shaped fingers 10 is less than the diameter of a golf ball 24, shown by dotted lines, so that there is no possibility of a ball being missed by the fingers 10. If a ball should be located between the fingers 10 and the ramp 11 when the machine is at rest, it will be scooped up by the plate 12 as soon as the machine is moved forwardly.

Fig. 3 illustrates one method of removably securing the fingers 11 in the shaft 5. The shaft 5 is provided with spaced transverse bores or holes 25, of sufficient diameter to receive two of the legs 26 of the fingers 11, and set screws 27 clamp the legs 26 in place. Thus, any one of the fingers 11 which may become broken or badly bent out of shape, by striking a rock or from any other cause, may be easily replaced without disturbing any of the other fingers.

In operation, this golf ball collector is preferably pulled ahead of whatever power plant may be used for motivation, such as a tractor or truck, by being attached to a draw bar extending forwardly of the operating machine. The collector may be used singly, or in multiple, like a gang lawnmower, by having the separate units attached to the usual draw bar construction for gang lawn mowers, and the whole attached to the forwardly extending draw bar. It is preferable to have the collecting units move ahead of the truck or tractor, so that the wheels of the latter will not ride over and force any of the golf balls into the ground before they are picked up. Satisfactory results have also been obtained with a single unit located in advance of each of the front wheels of the truck or tractor, and a gang of units drawn behind the truck or the like and spanning the distance between the two forward units.

The spaced rods 14 of the ramp 11 permit twigs, dirt, stones, grass clippings, and the like to fall through to the ground, and the perforated bottom of the basket 16 is useful in cleaning the collected golf balls by turning a hose on them while they are still contained in the basket. This may be done while the basket is still in place in the col-

lecting device, or after the basket has been removed to some more convenient location.

What I claim is:

1. A golf ball collector comprising a frame, a shaft journalled in said frame, traction wheels secured on opposite ends of said shaft, a plurality of U-shaped spring fingers secured in said shaft in spaced relationship, on opposite sides of said shaft, the fingers on one side of said shaft being staggered relative to the fingers on the opposite side of said shaft, the spacing of said fingers being less than the diameter of a golf ball, and a basket removably supported in said frame for receiving golf balls moved toward said basket by said spring fingers.

2. In a golf ball collector, a frame, a shaft journalled in said frame, traction wheels secured on said shaft, a plurality of U-shaped spring fingers having the free ends of their leg portions removably secured in said shaft, said fingers being arranged in spaced, parallel relationship in diametrically opposite rows, the spacing of said fingers being less than the diameter of a golf ball, and a receptacle removably supported in said frame for receiving golf balls forced toward said receptacle by said spring fingers.

3. In a golf ball collector, a frame, a shaft journalled in said frame, traction wheels secured on said shaft, a plurality of U-shaped spring fingers having their free ends removably secured in said shaft, said fingers being arranged in spaced, parallel relationship in diametrically opposite rows and having their outer end portions bent away from the direction of rotation of said shaft, the spacing of said fingers being less than the diameter of a golf ball, and the spacing between the legs of said fingers being also less than the diameter of a golf ball, and a receptacle supported on said frame for receiving golf balls forced toward said receptacle by said spring fingers.

4. In a golf ball collecting device, a reel comprising a shaft, means for revolving said shaft, a plurality of spring fingers removably secured in said shaft in spaced parallel relationship and in diametrically opposite rows, the fingers in one row being staggered relative to the fingers in the opposite row, the spacing of said fingers being less than the diameter of a golf ball.

5. In a golf ball collecting device, a reel comprising a shaft, means for revolving said shaft, a plurality of U-shaped spring fingers having their free ends removably secured in said shaft, the spacing of the arms of said fingers and the spacing between said fingers being less than the diameter of a golf ball, and the outer ends of said fingers being bent away from the direction of rotation of said shaft.

6. A golf ball collector comprising a frame, a shaft journalled in said frame, traction wheels secured on opposite ends of said shaft, a plurality of U-shaped spring fingers secured in said shaft in spaced, parallel relationship, the spacing of said fingers being slightly less than the diameter of a golf ball, a ramp secured in said frame and slanting upwardly and rearwardly from a leading edge located close to the bottom of and in juxtaposition to a cylinder of rotation defined by said spring fingers, and a golf ball receptacle removably supported in said frame rearwardly of said ramp, with the front edge of said receptacle located below the rear edge of said ramp.

7. A golf ball collector as defined in claim 6, said ramp being in the form of a grid, with the spaces between the solid elements of said grid slightly less than the diameter of a golf ball, and

5

said receptacle having a perforate bottom, the perforations in said bottom being less in diameter than the diameter of a golf ball.
